UNITED STATES PATENT OFFICE

FRED ASHWORTH, OF BEVERLY, MASSACHUSETTS, ASSIGNOR TO UNITED SHOE MACHINERY CORPORATION, OF PATERSON, NEW JERSEY, A CORPORATION OF NEW JERSEY

PRESSER-FOOT MECHANISM FOR SEWING MACHINES

Application filed April 19, 1919, Serial No. 291,267. Renewed July 13, 1923.

This mechanism relates to sewing machines and more particularly to presser foot mechanisms for such machines.

The invention constitutes an improvement 5 in presser foot mechanisms of the type in which the presser foot is locked in work-clamping condition during the stitch formation to hold the work securely, and is unlocked when the feed movement of the work 10 takes place to allow the work to be fed forward between the work support and presser foot. The invention is particularly designed to be applied to machines of the class employed in sewing outsoles to the welts of welted 15 shoes and is illustrated in this application as embodied in a machine of this class, but it is also applicable to other machines.

One object of the present invention is to produce an improved presser foot mechanism 20 of this type which is simple in construction and reliable in operation, which is not subject to undue wear, and which will operate in an efficient manner when the parts become worn by long continued use.

Another object of the invention is to produce a novel and improved presser foot mechanism which may be readily applied to certain machines for sewing outsoles now in common commercial use.

With these objects in view, the invention consists in certain novel and improved constructions, arrangements and combinations 30 of parts hereinafter described and particularly pointed out in the claims the advantages of which will be understood and appreciated by those skilled in the art.

The features of the invention will be readily understood from the accompanying drawings illustrating a machine embodying the 40 invention in its preferred form and the following detailed description of the constructions therein shown.

In the drawings Figure 1 is a view in side elevation of a portion of an outsole sewing 45 machine embodying the invention illustrating particularly the presser foot mechanism; and Fig. 2 is a view in side elevation of a portion of the mechanism shown in Fig. 1 illustrating the parts in different positions.

The outsole shoe sewing machine illustrat-

ed in the drawings is a machine of the same general type as that illustrated and described in applicant's Patent, No. 1,169,909, dated February 1, 1916, and the presser foot mechanism shown in the drawing is designed particularly to be applied to a machine having the construction and arrangement of parts shown in said patent. The machine illustrated comprises a curved hook needle 2, a curved work feeding awl 4, a work support 6, 55 and a presser foot 8.

The presser foot 8 is of the usual construction and is secured to the forward end of the presser foot lever 10 which is pivoted on the stud 12. In the present embodiment of the invention, the presser foot has the following mode of operation during each cycle of 60 stitch forming operations of the machine. During the action of the stitch forming devices in forming a stitch the presser foot is locked in clamping engagement with the work so that the work is tightly clamped between the presser foot and the work support. During the feeding of the work, however, 65 the presser foot is unlocked and then rests lightly on the work so as to offer practically no resistance to the feeding movement of the work. At the end of the feeding movement of the work, the presser foot is pressed into engagement with the work with a comparatively heavy pressure so as to clamp the stock firmly against the work support, and is then locked in position. The presser foot remains locked until the beginning of the feeding operation, when it is again unlocked, 70 the cycle of operations being repeated.

The locking mechanism for the presser foot comprises a wedge block 14 pivotally supported on the lower end of a link 16 which is pivotally connected at its upper end with the rear end of the presser foot lever 10. The lateral faces of the wedge block 14 are preferably arranged at a relatively small acute angle to each other, as shown in the drawings. A contact, or guide plate 18, secured 75 to the frame, is arranged to engage the rear face of the wedge block 14 and acts to limit the movement of the wedge block laterally in one direction. A longitudinally movable, locking wedge block 20 is arranged to engage 80

the forward face of the wedge block 14 to lock the same from downward movement. The locking wedge block is confined between the wedge block 14 and a contact or guide plate 22 secured to the frame, the rear face 5 of which is inclined to a slight degree relatively to the forward face of the contact plate 18 so that these faces converge downwardly, the locking wedge block being shaped to fit 10 in the recess between the wedge block 14 and the rear face of the contact plate 22.

The locking wedge block is pivotally supported on the lower end of a link 24, the upper end of which is pivotally connected 15 with the forward end of one arm of a lever 26 pivoted on a stud 28. The lever 26 is acted upon by a spring 30 connected with another arm thereof which tends to swing the lever in a direction to elevate the locking wedge block 20. When the locking wedge block 20 is held by the action of the spring 30 in its upper position in engagement with the wedge block 14 and with the contact plate 22, the wedge block 14 is clamped with considerable pressure between the locking wedge block and the contact plate 18. The force exerted by the spring 30 on the locking wedge block 20, tending to move the locking wedge block upwardly, has a resultant greater than 30 said force, which tends to move the wedge block 14 upwardly, and the presser foot lever 10 is thus acted upon to force the presser foot against the work with a heavy pressure to clamp the work. When the locking wedge 35 block is in locking position any tendency to lift the presser foot, and thereby to move the wedge block 14 downwardly, will greatly increase the pressure of the rear face of said wedge block against the forward face of the 40 plate 18, the pressure of the forward face of said wedge block against the rear face of the locking wedge block 20 and the pressure of the locking wedge block against the rear face of the contact plate 22. The frictional action 45 of these contacting faces resists any tendency to downward movement of the wedge block 14. The area of contact of these faces in the present construction is considerable and the frictional resistance exerted thereby is sufficient effectively to counteract any tendency 50 to overcome the resultant force of the spring 30. The locking wedge block, therefore, will hold the presser foot locked securely in clamping engagement with the work.

55 The locking wedge block is held by the coiled spring 30 in locking position during the greater part of each cycle of operations of the machine. Just before the work is fed, 60 however, the locking wedge block is depressed against the action of said coiled spring, as shown in Fig. 1. The depression of the locking wedge block releases the same from forcible engagement with the wedge block 14, so 65 that the latter wedge block is then free to

move downwardly and the presser foot is relieved from clamping engagement with the work. The presser foot may be lifted from the work as the locking wedge block is depressed, or the presser foot may then be held lightly in engagement with the work by the action of a relatively light spring so that it offers practically no resistance to the feeding of the work between the presser foot and work support. When the feeding of the work has been completed the locking wedge block 20 is again moved upwardly by the action of the coiled spring 30 thereby, through its action on the wedge block 14, forcing the presser foot firmly into engagement with the work 70 and locking the same in position.

The mechanism for thus actuating and controlling the locking wedge block comprises a rod 34 pivotally connected at its lower end by a pin 36 with another arm on the lever 26. Upon the upper end of the rod 34 is slidably mounted a sleeve 38 in a slot in which is pivoted at 40 a gripping arm or lever 42 having an eccentric face arranged to engage a flat surface formed on the rod to grip the rod. The forward end of the gripping lever 42 is pivotally connected with the forwardly extending arm of a cam lever 44 pivoted on a stud 46, the rearwardly extending arm of which carries a cam roll 48 engaging in a cam groove in a cam disk 50 mounted on the main shaft 52 of the machine. The sleeve 38 is acted upon by a coiled spring 54 surrounding the rod 34 and interposed between the sleeve and a clamp block 55 clamped adjustably on the rod by means of a clamping screw which tends to move the sleeve upwardly relatively to the rod. The upward movement of the sleeve is limited by means of a stop arm 57 formed on the frame, the forward end of which is arranged to engage the upper end of the sleeve as shown in Fig. 2.

The mechanism for actuating and controlling the locking wedge block 20, described above, has the following mode of operation. When the forward arm of the cam lever 44 is in its uppermost position the upper end of the sleeve 38 is held in engagement with the stop arm 57 by the action of the coiled spring 54 and the eccentric portion of the gripping lever 42 is held out of engagement with the rod 34, all as shown in Fig. 2. The locking wedge block 20 is then held in its upper limiting or locking position by the action of the coiled spring 30, the strength of the coiled spring 54 which then tends to move the rod 34 downwardly, and to swing the lever 26 in a direction to depress the locking wedge block, being very slight as compared with that of the spring 30. When the forward arm of the cam lever 44 is swung downwardly the gripping lever 42 is first swung downwardly about its pivotal connection with the sleeve 38 until the eccentric portion of the gripping 100

lever engages the rod 34 and grips the rod, after which the gripping lever, the sleeve and the rod 34 are moved downwardly together thereby swinging the lever 26 in a direction to depress the locking wedge block. As the forward arm of the cam lever 44 swings upwardly, the eccentric portion of the gripping lever 42 is held in gripping engagement with the rod 34 until the upper end of the sleeve 38 engages the stop arm 57, after which the gripping lever swings upwardly about its pivotal connection with the sleeve thereby releasing the eccentric portion of the gripping lever from engagement with the rod 34. 10 The release of the rod allows the locking wedge block 20 to be forced upwardly by the action of the spring 30 to force the presser foot firmly into engagement with the work and to lock the same in position. With this 15 mechanism for actuating and controlling the locking wedge block, the wedge block is moved a relatively slight uniform distance during each cycle of the machine to unlock the presser foot, regardless of the locking position 20 of the locking wedge block which varies with variations in the position of the presser foot due to changes in the thickness of the work.

To enable the presser foot to be lifted during each cycle of operations, if desired, a pin 25 58 is mounted in the wedge block 14 and is arranged to project therefrom beneath the clamp block 55. When it is desired to allow the presser foot to remain in engagement with the work as the locking wedge block 20 is depressed to unlock the presser foot, the clamp block 55 is adjusted on the rod 34 so that it will not engage the pin 58 during the downward movement of the rod. The presser foot is then held lightly in engagement with the 30 work by means of a coiled spring 59 connected at its upper end with the arm 57 and at its lower end with the rear end of the presser foot lever 10. When it is desired to lift the presser foot during each cycle of operations of the machine, the clamp block 55 is adjusted on the rod 34 so that it will engage the pin 58 during the downward movement of the 35 rod 34 just after the locking wedge block 20 is depressed sufficiently to unlock the presser foot. The presser foot is then lifted by the downward movement imparted to the wedge block 14 by the clamp block 55, as shown in Fig. 1, as the rod 34 continues its downward movement. With this adjustment of the 40 block the presser foot will be lifted a substantially uniform distance from the work during each cycle of operations.

The machine illustrated is provided with a pull-off mechanism comprising thread 45 guiding eyes 60 and 61 formed on an arm 62 secured to a rock shaft 64, and a pull-off arm 66 arranged to operate between the thread guiding eyes, this mechanism having the same construction and mode of operation as the 50 pull-off mechanism illustrated and described

in applicant's patent referred to above. In order to vary the position of the thread-guiding eyes 60 and 61 with relation to the pull-off arm 66, so that the pull-off arm will operate to pull off the required quantity of thread during each cycle of operations in accordance with the thickness of the work, a second arm 68 is secured to the rock shaft 64 and is connected by a link 70 with the arm of the lever 26, which supports the locking wedge block. 70

The present machine is provided with mechanism for depressing the locking wedge block to unlock the presser foot and for actuating the presser foot lever to lift the presser foot when the presser foot is normally locked in work engaging position to permit the removal, insertion or adjustment of the work. This mechanism is constructed and arranged to be actuated automatically to unlock and lift the presser foot upon stopping the machine and also is adapted to be actuated manually. 80

In the construction illustrated this mechanism comprises a lever 72 pivotally mounted on the stud 12, and a link 74 pivotally connected at its upper end with a rearwardly extending arm on the lever 72, and having its lower end formed with a slot 76 in which engages the pin 36 which connects the rod 34 with the lever 26. The lever 72 is provided with an upwardly extending arm which is connected by a link or bar 78 with a lever pivoted at the rear of the main shaft 52, and adapted to be actuated from a cam carried by the shaft upon stopping the machine. The lever with which the rear end of the link 78 is connected and the mechanism for actuating the lever upon stopping the machine are fully illustrated and described in applicant's Patent, No. 1,233,539, dated July 17, 1917. The mechanism illustrated in said patent operates to swing the lever to which the rear end of the link 78 is connected rearwardly upon stopping the machine, and the link will thereby be moved longitudinally to the rear, and the lever 72 will be swung about the stud 12 in a direction to depress the link 74. 90

During the swinging movement thus imparted to the lever 72 the upper end of the slot 76 in the link engages the pin 36 and the lever 26 is thereby actuated to depress the locking wedge block 20. The downward movement of the link also depresses the rod 34 and as the rod moves downwardly the clamp block 55 engages the pin 58 and the presser foot lever is actuated to lift the presser foot. The lever 72 may be actuated manually to unlock and lift the presser foot by grasping the upwardly extending arm of the lever and swinging the same rearwardly. 100

The slot 76 in the link 74 allows the pin 36 to move independently of the link during the operation of the presser foot mechanism in each cycle of operations of the machine. 105

Having explained the nature and object of 110

the invention, and having specifically described a machine embodying the same in its preferred form, what is claimed is:

1. A sewing machine having, in combination, stitch forming devices, a work support, a presser foot, a presser foot carrier, a wedge block and connections between the same and the presser foot carrier, a locking wedge block for engaging the first wedge block, means for moving the locking wedge block to lock and unlock the carrier during each cycle and operations, a pull-off and connections between the locking wedge block and the pull-off for varying the thread drawing off action of the pull-off. 15
2. A sewing machine having, in combination, stitch forming devices, a work support, a presser foot, a presser foot lever, a link pivotally connected with the rear end of the presser foot lever, a wedge block pivotally supported on the link, a locking wedge block supporting lever, a link pivotally connected with the supporting lever, a locking wedge block pivotally supported on the link, guides 20 for the respective wedge blocks, and means for actuating said supporting lever to move the locking wedge block into and out of locking position during each cycle of operations. 25
3. A sewing machine having, in combination, stitch forming devices, a work support, a presser foot, a presser foot carrier, a wedge block and connections between the same and the presser foot carrier, a locking wedge block arranged to engage the first wedge 30 block on a plane inclined to the directions of movement of both wedge blocks, a lever on which the locking wedge block is supported, a spring acting on the lever and tending to swing the same in a direction to move the locking wedge block into locking position, and means for swinging the lever a substantially 35 uniform distance during each cycle of operations to move the locking wedge block out of locking position. 40
4. A sewing machine having, in combination, stitch forming devices, a work support, a presser foot, a presser foot carrier, a wedge block and connections between the same and the presser foot carrier, a locking wedge block 45 supporting lever, a locking wedge block supported on the lever, means for actuating the lever to move the locking wedge block into and out of locking position during each cycle of operations, pull-off mechanism comprising 50 an arm, thread eyes carried by said arm, a thread engaging pull-off arm operating between said thread eyes, a rock shaft to which the first arm is secured, a second arm secured to said rock shaft, and a link connecting the 55 locking wedge block supporting lever with the last arm. 60
5. A sewing machine having, in combination, stitch forming devices, a work support, a presser foot, two relatively movable cooperating wedge blocks arranged to contact with 65

each other on a plane inclined to the directions of movement of both wedge blocks for locking the presser foot, and means for relatively actuating said wedge blocks to lock and unlock the presser foot and for lifting the presser foot when the presser foot is unlocked during each cycle of operations. 70

6. A sewing machine having, in combination, stitch forming devices, a work support, a presser foot, a presser foot carrier, a wedge block and connections between the same and the presser foot carrier for moving said wedge block with the carrier, a locking, wedge block for engaging the first wedge block on a plane inclined to the directions of movement of both wedge blocks, and means for moving the locking wedge block to lock and unlock the carrier and for moving the carrier to lift the presser foot when the carrier is unlocked during each cycle of operations. 80

7. A sewing machine having, in combination, stitch forming devices, a work support, a presser foot, two relatively movable cooperating wedge blocks arranged to contact with each other on a plane inclined to the directions of movement of both wedge blocks and acting to lock and unlock the presser foot during each cycle of operations, and means for relatively moving the wedge blocks to unlock the presser foot and for lifting the presser foot when the presser foot is normally locked in work engaging position. 90

8. A sewing machine having, in combination, stitch forming devices, a work support, a presser foot, a presser foot carrier, a wedge block and connections between the same and the presser foot carrier for moving said wedge block with the carrier, a locking wedge block for engaging the first wedge block, means for moving the locking wedge block to lock and unlock the carrier and for lifting the presser foot comprising a longitudinally movable rod, a connection between the rod and the locking wedge block, a block secured to the rod, and a pin mounted on the first wedge block and arranged to be engaged by the block during the unlocking movement of the rod to actuate the first wedge block to lift the presser foot. 100

9. A sewing machine having, in combination, stitch forming devices, a work support, a presser foot, two relatively movable cooperating wedge blocks, means for relatively actuating the wedge blocks to lock and unlock the presser foot during each cycle of operations, and an adjustable device acting when adjusted in one position to lift the presser foot, and when adjusted in another position to allow the presser foot to remain in engagement with the work as the wedge blocks are relatively actuated to unlock the presser foot. 115

FRED ASHWORTH.
